CLAIM

The ornamental design for a computer, as shown and described.

DESCRIPTION

FIG. 1 is a front, top, left-side, perspective view of a computer showing our new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1; and,

FIG. 7 is a bottom plan view of the computer shown in FIG. 1.

The broken lines shown in the drawings represent portions of the computer that form no part of the claimed design.
